UNITED STATES PATENT OFFICE.

CLIFFORD A. CUTLER, OF BUFFALO, NEW YORK.

VARNISH-KILN.

1,105,623.

Specification of Letters Patent.

Patented Aug. 4, 1914.

Application filed May 28, 1912. Serial No. 700,256.

To all whom it may concern:

Be it known that I, CLIFFORD A. CUTLER, a citizen of the United States of America, residing at Buffalo, in the county of Erie and State of New York, have invented certain new and useful Improvements in Varnish-Kilns, of which the following is a full, clear, and exact description.

In most of the present kilns, condensing coils are used to cause a circulation of air in the kiln. In kilns of this type, the moisture in the air contained within the kiln is condensed by the condensing coils and taken out of the air, thus making the air inside of the kiln much drier than that on the outside thereof. In these kilns, the varnish is hardened or oxidized in air containing a great deal less moisture than the air outside of the kiln, and, as is well known to those skilled in the art, the wood upon which the varnish has been spread should not be treated to an excessive drying condition during the finishing process. In producing my invention, therefore, I have sought to provide a kiln which shall dispense with the use of condensing coils and in which the humidity of the air may be controlled and kept proportionately the same as that of the atmosphere outside of the kiln. This also prevents the upper surface of the varnish from hardening before the varnish underneath can dry.

Another object of my invention has been to provide a kiln which may be conveniently and easily installed in any factory at a comparatively small initial cost and one which shall be inexpensive to operate.

Another object of my invention has been to provide a kiln in which the oxygen contained in the air in said kiln may be replenished without causing a drop in temperature of the air contained in the kiln, thus greatly decreasing the time of oxidization of the varnish. Furthermore, the circulation of air in my kiln is in a general horizontal direction, so that, large surfaces, such, for instance, as table tops, will be dried as rapidly at the center thereof as at the edges and a large number of pieces may also be rapidly dried by placing them in a horizontal position on racks placed in the kiln.

Reference is to be had to the accompanying drawings forming part of this specification, in which like characters of reference

indicate like parts, throughout the several views of which:

Figure 1 is a plan view of my kiln. Fig. 2 is a side sectional elevation thereof. Fig. 3 shows an enlarged sectional view of a means for securing together the edges of two adjacent curtains. Fig. 4 is an enlarged sectional elevation of the bottom edge of one of the curtains and shows the curtain stick in place. Fig. 5 is a plan view of a modified form of kiln where only two curtains are employed. Fig. 6 is a sectional elevation of a single curtain and shows substantially the form the curtain takes when the kiln is in operation.

In the drawings, 8 represents the ceiling and 9 the floor line of any room in which my kiln is placed. Suspended from the ceiling 8 are porous curtains or permeable walls 10, which inclose the space forming my kiln. These curtains, which are preferably fabric, are hung from a stringer 11, or other suitable means secured to the ceiling 8. They extend from the ceiling 8 down to the floor 9 and each is preferably provided near the lower end with a batten 12, which extends across the full width of each of the curtains. This batten acts to stiffen the curtain at the lower edge and aids in keeping the curtain in place near the floor. Each of the curtains below the batten 12 is preferably provided with a projecting end 13 which is arranged to lie upon the floor 9 and when the curtain is in position, this projection serves to close the space between the curtain and the floor, even if there be inequalities in the upper surface of the floor. Each of the curtains 10 is provided with suitable means for raising them out of the way. This may be accomplished by any one of the well known means, but preferably as shown in the drawings, where 14 represents a cord secured to the batten 12 at one end and extending up the outside of the curtain, through eyelets or rings 16, secured to the same at suitable intervals, and over a pulley 15, secured to the ceiling 8.

Placed within the kiln and near one of the curtains is a radiator 17, which is for the purpose of heating the air contained in my kiln. This radiator is preferably of the hot-water type, which is provided with an opening at the top on one side and a like opening at the bottom on the opposite side.

18 represents the steam inlet and 19 the outlet thereof.

20 is a baffle plate which is placed between the radiator and the curtain 10 and serves to 5 deflect the air currents upwardly.

21 is a fan which preferably oscillates and which is placed in front of the radiator and operated to draw the air from the opposite side of the kiln and force it through the said 10 radiator. This fan may be dispensed with if desired, as there would be without it a natural circulation of air within the kiln, but the fan is preferably employed to increase that circulation and when used, it 15 permits the employment of a smaller radiator than otherwise.

When my kiln is employed in factories where there is considerable draft, it is advisable to employ some means to secure the 20 edges of adjacent curtains together. This may be carried out by the arrangement shown in Fig. 3, where 22 represents a post which is secured to the floor and is preferably disposed inside of the kiln and at each 25 corner thereof. Inclosing the posts on two sides are two strips of flat material 23, which are preferably secured together at right angles to each other. When in use, the two adjacent edges of the curtains 10 are placed 30 between one of the posts and one pair of the strips 23 and frictionally held in this position. The strips 23 are secured to the posts 22 by any suitable means.

25 represents a steam nozzle which is connected to the steam supply pipe 18 and provided with a valve 26. By means of this nozzle, steam may be admitted to the kiln, as desired, and thereby the humidity of the air may be increased.

40 In Fig. 5 I have shown a modified arrangement in case it is desired to place my kiln in the corner of a room and thus employ two walls 27 of the room for two of the 45 walls of the kiln. In some cases advantageous results may be obtained by this arrangement.

When my kiln is in operation, the air contained therein is drawn across the bottom of the kiln and blown through the radiator 50 by the fan 21. This air, as it passes through the radiator is heated and is deflected upwardly by the baffle plate 20. This air, because of its heated condition, as well as, because of the current produced by the fan, 55 will rise to the upper part of the kiln. The heated air, as it passes across the upper part of the kiln strikes the opposite curtain and the curtain at each side near their top, and as this air is higher in temperature than that 60 contained in the atmosphere outside of the kiln, it is cooled somewhat, which causes it to move downwardly toward the bottom of the kiln, where it is again drawn, by means of the fan and forced through the radiator, 65 when it is again heated. The curtains of my

kiln thus act as cooling surfaces but do not condense any of the moisture contained in the air. As the curtains are somewhat porous and permeable, some of the air, as it strikes the upper part thereof, will pass 70 therethrough and fresh air will be drawn in the kiln through the curtains at the bottom to take the place of that which has passed out through the top part of the curtains, as indicated by the arrows in Fig. 6. By this 75 means, the oxygen in the air contained within the kiln will be replenished and the hardening of the varnish greatly increased thereby.

One of the obvious, practical advantages 80 of my kiln is that it may be used at night and during the day the curtains thereof may be raised and the floor space which it occupies may thus be utilized for other purposes.

I have found in practice that the size of 85 my kiln is made preferably fifteen feet square and for this size kiln a radiator having about one hundred and fifty square feet of radiating surface is preferable.

Obviously, some detail modifications of 90 the device herein shown and described may be made, without departing from the spirit of my invention or the scope of the appended claims, and I do not wish to be limited to the exact embodiment herein shown and described.

Having thus described my invention, what I claim is:

1. A closed air kiln comprising at least one curtained wall, means for radiating heat 100 within the kiln, and means for driving air through said heat radiating means.

2. A closed air kiln comprising curtained walls, means for radiating heat within said walls, means for driving heat through said 105 heat radiating means, and means for sealing the lower edges of said walls.

3. A closed air kiln comprising curtained walls, means for radiating heat within said walls, and means for increasing the humidity 110 of the air contained within said walls.

4. A closed air kiln comprising curtained walls, means for radiating heat within said walls, means for passing air through said heat radiating means, and means for raising 115 and lowering said walls.

5. A closed, unpartitioned air kiln comprising curtain walls, means for radiating heat within said walls, means for driving air through said heat radiating means and means for increasing the humidity of the air 120 contained within said walls.

6. A closed, unpartitioned air kiln comprising curtain walls, means for radiating heat within said walls, means for driving air through said heat radiating means and means for securing together adjacent edges of said 125 walls.

7. A closed, unpartitioned air kiln comprising flexible, finely meshed and substan- 130

tially non-condensing walls, means for radiating heat within said walls and means for driving air through said heat radiating means.

5 8. A closed, unpartitioned air kiln comprising curtain walls, means for radiating heat within said walls, means for driving air through said heat radiating means, means for securing together adjacent edges 10 of said walls, and means for raising and lowering said walls.

9. A closed, unpartitioned air kiln comprising curtain walls, means for radiating heat within said walls, means for driving 15 air through said heat radiating means, means for securing together adjacent edges of said walls and means for increasing the humidity of the air contained within said walls.

20 10. A kiln comprising fabric walls, heat

radiating means within said walls, and a fan for driving air through said heat radiating means.

11. A kiln comprising fabric walls, heat radiating means within said walls, a fan for 25 driving air through said heat radiating means and a baffle plate disposed at the back of said heat radiating means.

12. A kiln comprising fabric walls, heat radiating means within said walls, an oscillating fan for driving air through said heat 30 radiating means and a baffle plate disposed at the back of said heat radiating means.

In testimony whereof, I have hereunto signed my name in the presence of two sub- 35 scribing witnesses.

CLIFFORD A. CUTLER.
